(57) **CLAIM**

The ornamental design for a hernia belt, as shown and described.

DESCRIPTION

FIG. 1 is a top, front perspective view of a hernia belt embodying our new design;

FIG. 2 is a top view thereof;

FIG. 3 is a bottom view thereof;

FIG. 4 is a side view thereof as seen from the right-hand side of FIG. 2;

FIG. 5 is a side view thereof as seen from the left-hand side of FIG. 2;

FIG. 6 is a rear view thereof;

FIG. 7 is a front view thereof;

FIG. 8 is a top view of an alternative embodiment of a hernia belt;

FIG. 9 is a bottom view thereof;

FIG. 10 is a top view yet another embodiment of a hernia belt; and,

FIG. 11 is a bottom view thereof.

The broken lines in the figures depict stitching and form no part of the claim.

1 Claim, 5 Drawing Sheets
